FOLDED CART

Harold Isaacs, 2583 Fenwick Road,
University Heights, Ohio 44118

Filed Mar. 19, 1971, Ser. No. 126,382

Term of patent 14 years

Int. Cl. D12—14

U.S. Cl. D14—3 M

FIG. 1

FIG. 2

FIG. 3

FIG. 4

FIG. 1 is a perspective view of the folded cart in accordance with my invention;

FIG. 2 is an end elevational view of the folded cart shown in FIG. 1;

FIG. 3 is a side elevational view typical of both sides of the folded cart shown in FIG. 1; and

FIG. 4 is an end view of the folded cart illustrating the opposite end of that shown in FIG. 2.

I claim:

The ornamental design for a folded cart, substantially as shown and described.
